UNITED STATES PATENT OFFICE.

EPHRAIM F. HERRINGTON, OF WEST HOOSICK, NEW YORK.

IMPROVEMENT IN HARVESTER FINGER-BEAM CATCHES.

Specification forming part of Letters Patent No. 175,090, dated March 21, 1876; application filed July 8, 1874.

To all whom it may concern:

Be it known that I, EPHRAIM F. HERRINGTON, of West Hoosick, in the county of Rensselaer and State of New York, have invented an Improved Harvester Finger-Beam Catch, of which the following is a specification:

My invention relates to harvesters of that class which have a finger-beam so hinged to the main frame as to be capable of being folded up against the side thereof, and a spring-catch to hold it in this position. The object of my invention is to enable the driver readily to release said catch by the use of his feet or hands.

To enable the driver to release the catch by the use of his foot, I provide the catch with a toe or projecting lug, against which he may press. A hand-lever linked to the catch enables him to attain the same end with his hand. This device may also be operated by the foot.

The subject-matter claimed is hereinafter specified.

In the accompanying drawings, Figure 1 represents a plan view of my improved device in the attitude it assumes when the finger-beam is locked in its upright position. Fig. 2 is a similar view with the catch retracted, and Fig. 3 a vertical section of the device on the line $x x$ of Fig. 1.

The catch A is provided with a holding-notch, a, in which the finger-beam is held when folded up toward or against the frame or tongue, and with a toe, b, to be acted upon by the driver's foot. The catch is mounted on a bracket, C, secured upon the frame or tongue of the machine, or the bracket may form part of the frame or tongue, and vibrates on a pivot-pin, c. A spring, e, in a recess in the bracket bears against a lip or flange on the catch, which projects into the recess, (see Fig. 3,) and tends to keep the catch always thrown forward into the position shown in Fig. 1. A lever, D, rocking upon a fulerum,

d, on the bracket, is connected by a link, d', or by a cord or chain, to the catch A.

The operation of the device is obvious. As the finger-beam is turned up against the frame, its back edge strikes against the nose c' of the catch, and shoves it back until the beam enters the notch a, when the spring e throws the catch forward, and holds the finger-beam securely. To release the catch, the driver presses on the toe b with his foot, and thus retracts the catch. He may produce the same result by pressing with his foot on the lever D, or work it by hand.

By connecting the link d' to the catch above instead of below the fulerum, it is obvious that the action of the lever would be reversed—that is, that it would then have to be drawn backward instead of being shoved forward.

This device obviously possesses great advantages over the spring-catches heretofore used, with no means of retracting the catch except to take hold of it directly by the fingers of the operator, as by my invention the operator, in his seat on the machine, is enabled to release the finger-beam from the catch by either foot, or by both feet, by his hand alone, or by both hand and foot together.

I claim—

1. The pivoted spring-catch A, constructed, as described, to operate directly upon the finger-beam, with a toe, b, to be acted upon by the foot of the driver while on his seat.

2. The combination of the bracket, the spring-catch adapted to operate directly upon the finger-beam, and the lever pivoted on the bracket, these members being constructed and operating substantially as set forth.

In testimony whereof I have hereunto subscribed my name.

E. F. HERRINGTON.
